(57) **CLAIM**

The ornamental design for a power tool coupling portion, as shown and described.

DESCRIPTION

Cross reference is made to copending U.S. design patent application Ser. No. 29/611,819 entitled “Power Tool Accessory” by Luescher et al., filed on Jul. 26, 2017.

FIG. 1 is a perspective view of a power tool coupling portion showing our new design;

FIG. 2 is a front elevational view of the power tool coupling portion of FIG. 1;

FIG. 3 is a rear elevational view of the power tool coupling portion of FIG. 1;

FIG. 4 is a right side elevational view of the power tool coupling portion of FIG. 1;

FIG. 5 is a left side elevational view of the power tool coupling portion of FIG. 1;

FIG. 6 is a top plan view of the power tool coupling portion of FIG. 1; and,

FIG. 7 is a bottom plan view of the power tool coupling portion of FIG. 1.

The broken lines shown in the drawings illustrate portions of the power tool coupling portion that form no part of the claimed design.
